UNITED STATES PATENT OFFICE.

VETRELL CARROLL, OF LOWELL, MASSACHUSETTS.

PICKER CHECK.

Application filed March 5, 1923. Serial No. 622,753.

To all whom it may concern:

Be it known that I, VETRELL CARROLL, a citizen of the United States, and resident of Lowell, county of Middlesex, State of Massachusetts, have invented an Improvement in Picker Checks, of which the following description, in connection with the accompanying drawing, is a specification, like characters on the drawing representing like parts.

This invention relates to a picker check for looms and has for its general object to provide a novel picker check which is simple in construction and which is easily applied to any loom and which functions not only to check the picker on its backward movement but which serves to also prevent any rebound in the picker.

The features wherein the invention resides will be more fully hereinafter set forth and then pointed out in the appended claim.

In the drawings wherein I have shown a selected embodiment of my invention, Fig. 1 is a plan view of one end of the lay of a loom with the shuttle box thereon and showing my improved picker check in its normal position;

Fig. 2 is a similar view showing the shuttle box and the picker check in operation;

Fig. 3 is a section on the line 3—3, Fig. 1;

Fig. 4 is a section on the line 4—4, Fig. 1, showing the picker check in elevation;

Fig. 5 is a similar sectional view showing the picker check in section.

Inasmuch as my present invention relates simply to the picker check I have shown only such portions of a loom as is necessary to illustrate the invention.

1 indicates the lay of a loom having the shuttle box 2 thereon and provided with the vertical slot or opening 3 in which the picker stick 4 operates, said picker stick carrying the usual picker 5. The shuttle box is shown as provided with a shuttle binder 6 which may be of any suitable or usual construction.

The parts thus far described are or may be all as usual in looms and form no part of my present invention.

50 My improved picker check is pivotally mounted on the lay adjacent the end of the shuttle box and is acted on by a spring which normally holds it in the path of the picker so that when the shuttle enters the box and moves the picker back to the end of the slot 3 the picker will engage the picker

check and the latter will function to check the movement of the picker. The picker check is also constructed so that it has a binding action on the picker when the 60 picker stick is at the outer limit of its movement, such binding action being sufficient to prevent rebound of the picker.

This picker check is shown at 7 and it is pivotally mounted on a bolt 8 which extends 65 vertically through the lay 1 adjacent the end of the shuttle box and on the opposite side thereof from the binder. The bolt 8 is shown as a shouldered bolt, it having the portion 9 of smaller diameter than extends 70 through the lay 1 and the upper portion 10 of larger diameter extending above the lay, said bolt having the shoulder 11 which rests on top of the lay. The bolt is secured in the lay by means of a nut 12 screwed onto its 75 lower end. The picker check 7 is formed with the picker-engaging portion 13 that has a vertical dimension substantially equal to the vertical dimension of the picker 5 and with a heel portion 14 of less thickness provided with an opening 15 through which the portion 10 of the bolt 9 loosely passes. The portion 10 of the bolt having the larger diameter is considerably longer than the thickness of the heel portion 14 so that the 80 head 17 of the bolt is spaced from said heel portion 14.

A spring 16 encircles this portion 10 and has one end anchored to the head 17 as shown at 18 and the other end anchored to 85 the picker check as shown at 19.

The picker-engaging portion 13 of the picker check is formed with the curved picker-engaging face 20. The parts are so constructed that the picker check normally 90 occupies a position shown in Fig. 1 with the portion 13 thereof extending part way across the opening 3. The spring 16 tends to hold the picker check in this position but allows it to swing backwardly into the position shown 100 in Fig. 2 and during the swinging movement of the picker check from the position shown in Fig. 1 to that shown in Fig. 2 the spring will be wound up or placed under increased tension.

105 The operation of the device will be readily understood from the foregoing. After the shuttle has been thrown from the shuttle box the picker check will occupy the position shown in Fig. 1. When the shuttle returns to the shuttle box it engages the picker 110 5 and carries the picker stick backwardly to

the end of the slot 3 and during the last portion of the movement of the picker stick the picker will engage the curved face 20 of the picker check and force the latter back into 5 the position shown in Fig. 2 against the action of the spring 16. This will apply a frictional pressure to the picker which will resist in retarding and checking this movement.

- 10 The picker check is so constructed that the picker wipes by it in its backward movement so that when the picker finally comes to rest at the end of the slot as shown in Fig. 2 the picker check is bearing against 15 the side of the picker. Owing to this construction and to the shape of the curved face 20 of the picker check the latter functions when in the position shown in Fig. 2 to prevent rebound of the picker and thus holds 20 it in its rearward position. The picker check, therefore, functions both as a means for retarding the backward movement of the picker and as a means for preventing rebound of the picker.
- 25 The binder 6 operates in usual manner to check the momentum of the incoming shuttle and my improved picker check functions separately or independently from the binder to assist in checking the final movement of 30 the picker. The use of the shouldered bolt 8 provides means whereby the tension of the spring 16 can be adjusted. If it is desired to increase the checking action of the

picker check 13 then the nut 12 may be loosened and the bolt 8 turned in the lay so 35 as to increase the tension of the spring 16, and by then tightening the nut so as to clamp the shoulder 11 firmly against the top of the lay the bolt will be retained in such 40 adjusted position and the increased tension on the spring will be maintained. The picker check, therefore, is not only independent from the binder but can be adjusted independently from the binder.

The device is extremely simple in construction and can be readily applied to any 45 loom.

I claim.

In a loom, the combination with a lay 50 having a shuttle box thereon and a shuttle binder, of a picker stick carrying a picker, a shouldered bolt extending vertically through the lay adjacent one end of the shuttle box and on the opposite side thereof from the binder, a picker check pivotally 55 mounted on the bolt and situated above the lay, a spring encircling the bolt and having one end anchored thereto and the other end connected to the picker check and a nut on the bolt co-operating with the shoulder 60 to hold the bolt in adjusted position with the spring at the desired tension.

In testimony whereof, I have signed my name to this specification.

VETRELL CARROLL.
